LINOLEUM OR SIMILAR HARD SURFACE COVERING

Filed Feb. 15, 1929

Inventor:
Frank Cartwright,
By *S. J. Smith*
Attorney.

UNITED STATES PATENT OFFICE.

FRANK CARTWRIGHT, OF TRENTON, NEW JERSEY, ASSIGNOR TO THE GEORGE W. BLABON COMPANY, OF PHILADELPHIA, PENNSYLVANIA, A CORPORATION OF PENNSYLVANIA.

DESIGN FOR LINOLEUM OR SIMILAR HARD-SURFACE COVERING.

Application filed February 15, 1929. Serial No. 30,077. Term of patent 3½ years.

To all whom it may concern:

Be it known that I, FRANK CARTWRIGHT, a citizen of the United States, residing in the city of Trenton, in the county of Mercer and State of New Jersey, have invented a new, original, and ornamental Design for Linoleum or Similar Hard-Surface Covering, of which the following is a specification, reference being had to the accompanying drawing, forming a part thereof.

The figure is a plan view of a section of linoleum or similar hard surface covering

showing my new design, the several spaces being so shown as to indicate contrast in color or shade with the immediately adjacent spaces but the several styles of stippling are not intended to represent particular colors.

I claim:

The ornamental design for linoleum or similar hard surface covering as shown and described.

In testimony whereof I have hereunto set my hand this 31st day of January, 1929.

FRANK CARTWRIGHT.
